US0D1109142S

(12) **United States Design Patent** (10) **Patent No.:** **US D1,109,142 S**
(45) **Date of Patent:** **** Jan. 13, 2026**

(54) **NOTEBOOK COMPUTER**

(71) Applicants: **MICRO-STAR INT'L CO., LTD.**,
New Taipei (TW); **MSI**
ELECTRONIC (KUN SHAN) CO., LTD., Suzhou (CN)

(72) Inventors: **Jen Yu Chiang**, Taoyuan (TW); **Han Sheng Chen**, Taoyuan (TW); **Ko ting Hung**, Taichung (TW)

(73) Assignees: **MICRO-STAR INT'L CO., LTD.**,
New Taipei (TW); **MSI**
ELECTRONIC (KUN SHAN) CO., LTD., Suzhou (CN)

(**) Term: **15 Years**

(21) Appl. No.: **29/929,730**

(22) Filed: **Feb. 23, 2024**

(30) **Foreign Application Priority Data**

Jan. 10, 2024 (TW) 113300119

(57) **CLAIM**

The ornamental design for a notebook computer, as shown and described.

DESCRIPTION

FIG. 1 is a top, front and right side perspective view of a notebook computer showing our new design;

FIG. 2 is a top, rear and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is an enlarged view of the encircled portion 8 shown in FIG. 1;

FIG. 9 is an enlarged view of the encircled portion 9 shown in FIG. 2; and,

FIG. 10 is an enlarged view of the encircled portion 10 shown in FIG. 5.

The evenly spaced dashed broken lines depict unclaimed portions of the notebook computer.

The dash-dot lines depict the limits of the enlarged views and form no part of the claimed design.

1 Claim, 8 Drawing Sheets
